Robert J. Slavsky and John R. Slavsky,
Detroit, Mich.

Application June 30, 1948, Serial No. 147,306

Term of patent 14 years

(Cl. D22—3)

To all whom it may concern:

Be it known that we, Robert J. Slavsky and John R. Slavsky, citizens of the United States, residing at Detroit, in the county of Wayne and State of Michigan, have invented a new, original, and ornamental Design for Knife Handle, of which the following is a specification, reference being had to the accompanying drawings, forming part thereof.

We claim:

The ornamental design for a knife handle as shown.

ROBERT J. SLAVSKY.
JOHN R. SLAVSKY.
